UNITED STATES PATENT OFFICE.

RICHARD K. HOHmann, OF SIOUX CITY, IOWA

ROTARY-HOOK SEWING MECHANISM.

1,299,468.

Specification of Letters Patent.

Patented Apr. 8, 1919.

Application filed December 14, 1910. Serial No. 136,986.

To all whom it may concern:

Be it known that I, RICHARD K. HOHmann, a citizen of the United States, residing at Sioux City, Woodbury county, State 5 of Iowa, have invented certain new and useful Improvements in Rotary-Hook Sewing Mechanism, of which the following is a specification.

This invention relates to rotary hook sewing mechanism and particularly to such a mechanism adapted to rotate toward the operator or front of the machine with a high angular velocity. The objects of the invention are to provide a sewing mechanism of 10 this type so constructed and arranged that it will accommodate a large bobbin carrying a greater length of thread than heretofore possible; to provide means to deliver the bobbin thread at the right of the needle as viewed from the front of the machine; to provide means whereby the thread loop as it is drawn through the needle opening and into the cloth does not make a sharp bend at the edge of the opening, thereby permitting 15 the use of a weaker tension in connection with the take up; to provide means to cooperate with an inclined front wall on the race having a bobbin eccentrically arranged therein to aid in leading the outer limb of 20 the thread loop onto the front surface of the bobbin casing and race, thus making it possible to make the rotary hook and race of minimum diameter; to provide a novel means for preventing the bobbin casing 25 from turning relative to the race or carrier; and to construct the parts so that the thread loop will slide over the surfaces thereof with a minimum of resistance, thereby permitting 30 high sewing speeds. Other objects will be 35 apparent from the description taken in connection with the drawings, in which,

Figure 1 is a rear elevation of an assembled loop taker, carrier and bobbin and showing the parts in the positions they occupy as the beak of the rotary loop taker is 40 seizing the thread loop from the needle;

Fig. 2 is a side elevation of the assembled device in the position shown by Fig. 1;

Fig. 3 is a side elevation and showing the 45 position of the parts after the loop taker has rotated through an angle of a little more than 90°;

Fig. 4 is a side elevation showing the 50 thread and device in the positions which they 55 occupy when the loop taker has rotated

through approximately $\frac{1}{2}$ of a turn from the loop seizing position shown in Fig. 1;

Fig. 5 is a front elevation of the device showing the thread loop as it is being withdrawn from the projecting finger of the bobbin casing;

Fig. 18 is a sectional view of the assembled device and showing the spider or ring for mounting the same on the hook shaft of the sewing machine.

One of the principal defects of high speed

power driven sewing machines as constructed at present consists in the limitation of the size of the bobbin and consequently of the supply of thread which said machines will accommodate. The bobbin is so small, 100 and especially so in machines having the hook rotating toward the operator, that it must be replaced at very frequent intervals with a consequent loss of time and production of the machine. It is the principal object of this invention to provide a sewing machine mechanism of the type having the hook rotating toward the operator which will accommodate and use a bobbin carrying a much larger supply of thread than 110

any heretofore in commercial use. It is obvious that the size of the bobbin may be increased either by making it longer or of greater diameter or by a combination of these two dimensions. In any case if the size of the bobbin is increased the size of the thread loop which must be cast around the bobbin is also greater and, because of this, severe strains are placed on the thread, and the mechanism must be designed and constructed with the greatest care in order to operate successfully. Because of the increased size of the thread loop a larger amount of thread is drawn through the eye of the needle and later must be pulled up by the take-up. Consequently the take-up must be designed to give a larger amount of motion to the thread and the surfaces over which the thread loop is cast must be designed so that there will be no place where the thread will catch, or dirt, oil, lint or other things collect, to thereby produce friction as the thread is drawn over them. If the bobbin is made longer in order to increase the quantity of thread it will carry, the inclined edge of the beak or other means for casting one limb of the thread loop toward the rear of the bobbin must be so long that in the short time taken for the rotation of the hook from its top to its bottom position, or 180° , the thread will not have passed to the rear of the bobbin casing when the hook has reached said lower position, with the result that the thread will be caught between the hook and carrier, thus producing a snarl. On the other hand, if the diameter of the bobbin is increased in order to carry a larger amount of thread the peripheral speed of the hook will be correspondingly increased so that the loop seizing beak will strike the thread loop at the needle with considerable violence and the great acceleration placed on the thread at that instant will produce considerable tension therein with a liability of breakage. By judiciously increasing both of these dimensions, that is, the length and diameter, and constructing the parts of the mechanism to properly coöperate with the increased size of the bobbin, a rotary hook mechanism of the type rotating toward the operator may be produced which can be operated at a rate of 3,000 or 4,000 stitches per minute and yet carry a bobbin having several times as much thread thereon as any machine heretofore used.

As clearly shown in the drawings, the mechanism comprises a loop taker, a carrier or race mounted therein and a thread or bobbin case carried by the carrier. Referring to Figs. 6 to 9, inclusive, which show the loop taker, it will be noted that it consists of a cylindrical ring 20 provided at the rear end thereof with apertures 21 for connection to a

table attached to the hook shaft of the sewing machine. Of course, any other suitable means might be used for mounting the said loop taker on the hook shaft. Wherever possible the ring is formed with apertures 70 such as 22 for the purpose of reducing the weight thereof and distributing the weight so that the loop taker will be in dynamic balance. At the front end thereof the ring is formed with a notch 23 extending about 75 half way axially toward the rear end. One of the walls of this notch is inclined as at 24 whereby the meeting of the same with the front wall of the ring forms a pointed beak 25. This inclined wall 24 is for the purpose 80 of carrying one limb of the thread loop toward the rear of the bobbin casing. As means is provided on the carrier for guiding the said limb the remaining distance toward the rear of the bobbin casing, it is not necessary to have the inclined wall 24 extend for as great a distance toward the rear of the loop taker as it would be if this wall alone carried the said limb of the thread loop the entire distance to the rear of the bobbin casing. At the edge of the notch 23 opposite the inclined wall 24 a blunt circumferentially extending projection or nose 26 is provided, for a purpose which will be described later. The interior of the ring at the front end thereof is formed with an inwardly extending radial flange 27 which coöperates with the carrier to hold the latter in position in the loop taker. As clearly shown in the figures, especially Fig. 8, this flange does not extend entirely around the circumference of the ring but is omitted at the notch 23. A combined deflector and thread guiding member 29 is arranged to extend circumferentially across and over the notch 23 and 100 partially around the ring. As clearly shown in Fig. 8, this member extends around the ring for substantially 270° and has its ends attached to the same in any suitable manner, such as by means of the screws 30. It will be observed that the portion of the member 29 which extends across the notch 23 has its front edge 31 or the edge adjacent to the beak 25, spaced back slightly from the front edge of the ring, and that this forward edge 105 of the member 29, as it approaches the base of the beak 25, is curved toward the front edge of the ring. Thus, this curved portion 31 of the forward edge of the member 29 is arranged at an opposite inclination with respect to the inclined edge 24 of the beak 25 and thereby constitutes a deflecting surface to carry the upper thread of the thread loop toward the front end of the loop taker. At the base of the beak 25 and at the forward 110 edge of the inclined surface 31 the member 29 is formed with a lug or inwardly extending projection 32 which fits tightly in a recess 33 formed in the ring 20. Thus it will be apparent that this lug or projection 115

32 forms a throat between the deflector and the beak. Heretofore it has been the practice to form this throat by attaching one member to another and although the greatest accuracy were used a slight crack generally appeared between the members in which lint, grease, and dirt would accumulate and cause broken threads. It will be observed that by providing a lug on one of the members extending into a recess in the other, no cracks result and furthermore the thread passes over a very small surface of the lug and as the surface is so very small it is obvious that it does not afford opportunity for the lodgment of dirt, grease, or other foreign matter. Moreover, because of the simple structure, the device can be made very cheaply and secured in position without the requirement of a skilled workman. The remaining portion of the member 29 which extends from the base of the beak 25 around the ring for about 180° is provided with an inclined flange, or wall 34 which extends axially outward from the front edge of the ring and is inclined inwardly toward the axis of the same. This wall is therefore part of the surface of a cone and may be designated as a partial conical wall or an inclined front wall. The function of this wall 34 is to aid in guiding the front limb of the thread loop onto the inclined front wall of the race or carrier, as will be more fully explained hereafter. This inclined wall 34 could be omitted from the ring, the member 29 extending across the notch 23 only, and the device would operate successfully, but I prefer to employ the said wall, as it permits slightly decreasing the diameter of the ring.

The carrier or race which is adapted to be used with this loop taker will now be described. Referring to Figs. 10, 11, 12 and 14 to 17, inclusive, it will be observed that this carrier or race comprises a casting having a bearing rim 35 which, near the top of the carrier, is formed with a hook 36 facing or pointing toward the top. Opposite this hook the bearing rim is formed with a nose or blunt hook 37. The periphery of the bearing rim may be formed with a lubricating channel 38. The rear of the casing consists of a circular wall 39 which is connected to the bearing rim by means of an inclined wall 40. At the center of the rear wall 39 the projecting post or pin 51 is mounted which is adapted to receive and hold in position the thread or bobbin case. As clearly shown in Figs. 12 and 15, the axis of this pin is located eccentrically with respect to the axis of the bearing rim 35, that is, it is located below and to the side opposite the hook 36 with respect to the axis of the bearing rim. Because the center of the rear wall 39 is eccentric with respect to the bearing rim it will be observed that the inclination of the connecting wall 40 varies, that is, re-

ferring to Figs. 16 and 17, the left hand portion of the inclined wall 40 is more nearly vertical than the right hand portion shown in these figures, and the bobbin casing is mounted eccentrically in the carrier for this very purpose, as will be explained later. This inclined wall 40 is formed with an aperture 41 extending between the hooks 36 and 37 and to the rear circular wall 39 and the edge of this aperture adjacent the hook 36 is formed so that it constitutes a surface flush and tangent to the hook, whereby the limb of the thread loop caught by the hook 36 will be guided by the said smooth edge to the rear of the carrier. As illustrated in Figs. 10, 11 and 18, the bobbin casing projects forwardly of the bearing rim 35 and in order to guide the front limb of the thread loop onto the front surface of the bobbin casing an inclined front wall 42, similar to the rear wall 40, is provided and extends from the bearing rim to the front of the bobbin case. It should be noted, however, that this wall is not continuous entirely around the bobbin case but merely extends from adjacent the hook 36 to the bottom of the bobbin casing, as viewed in Figs. 12 and 15. At the top and front of the carrier this wall 42 is constructed to extend vertically upward to form two spaced apart shoulders 43 and 44, this portion being connected to the bearing rim adjacent the hook 37 by means of a web 45. The shoulders 43 and 44 are provided to loosely receive therebetween a lug 46 on a stationary member 47 (Figs. 1 and 2), whereby the carrier is prevented from rotating with the loop taker. Just below this lug 46 the front faces of the shoulders are formed with a concave depression 48 for the purpose of guiding the thread under the said lug 46. The outer edge of the front inclined wall 42 is not joined directly to the bearing rim 35 but is spaced therefrom, thereby forming a groove 52. As fully explained in my Patent No. 1,105,197, granted July 28, 1914, it is necessary to have the walls 40 and 42, shown especially in Figs. 16 and 17, or the walls at the right hand side of the bobbin case, as viewed in these figures, steeper with respect to the vertical than those at the left hand side. This is required because the thread loop is being drawn downward over said surfaces by the loop taker and, if the walls were not sufficiently inclined toward the axis, the limbs of the thread loop would not be carried toward the rear and front, respectively, of the bobbin case. On the other hand, as the loop when it reaches the left hand side of the structure is being pulled upward by means of the take-up, it is obvious that as both limbs of the loop have been moved to the end and front surfaces, practically no inclination of the side walls is required. Consequently by placing the bobbin casing eccentrically

trically within the carrier, the required inclination of the side walls is obtained and yet the maximum diameter of the casing is permitted. Furthermore, by locating the 5 axis of the bobbin case below, instead of on the same horizontal plane with the axis of the bearing rim of the carrier, the entire bobbin casing is located lower down in the carrier and consequently no part of the same 10 is in the path of movement of the needle. By forming the carrier with the groove 52 between the bearing rim and the outer edge of the inclined front wall, the diameter of the bearing rim is kept down be- 15 cause, if the groove were done away with and the said front wall were continued at the same inclination until it met the bearing rim, it is obvious that the diameter of the same would have to be increased. Thus by 20 forming the loop taker with the inclined projecting front wall at the base of the loop seizing beak so that the front limb of the thread loop is moved forward thereby and guided onto the inclined front wall 42 of 25 the carrier, the diameters of both the carrier and loop taker are kept at a minimum. The forward end of the post 51 is formed with a groove 53 which is adapted to coöperate with a latch 54 carried by the bobbin casing 30 to hold the same in position in the carrier. Any other suitable means might be used for retaining the bobbin casing in position within the carrier. The web 45 is continued for 35 a slight distance circumferentially around the bearing rim 35 and ends in an inclined shoulder 53. This extended portion of the web projects axially from the bearing rim only a slight amount to form the said shoulder which coöperates with the bobbin casing 40 for a purpose presently to be described.

Referring particularly to Fig. 13, the bobbin casing comprises a cylindrical shell 56 which is open at its rear end and at its front end carries the latch means 54. This shell 45 is adapted to receive the bobbin 57 having the thread 58 arranged thereon. The thread from the bobbin is adapted to be led through an aperture 59, thence for a short distance on the outer surface of the shell, then inward 50 through the slot 60 and outward through the aperture 61 in the shell, thence along the surface of the shell to the notch 62 in the tension member 67, then substantially vertically upward to the aperture 63 in the end 55 of the curved upwardly projecting finger 64 carried on the front of the bobbin casing. This aperture 63 forms one end of a short conduit 65 having an outlet in the end of the finger. From this outlet the thread is led 60 to the needle aperture 66 of the member 167. The slot 59 is curved and has the edge 68 formed on the arc of a circle with the aperture 61 as the center thereof. In bobbin cas- 65 ings as heretofore used the edge 68 has been straight and in consequence thereof when the

thread is being drawn from any portion of the bobbin except the central part there is a component of force due to the pull in the thread tending to carry said thread to the central part of the said straight edge. It 70 will be obvious that by forming the slot with the curved edge 68 there is no component tending to carry the thread to one side or the other. Thus, even if the thread is being withdrawn from the bobbin at the very 75 ends thereof it will pass in substantially a straight line from the bobbin to the aperture 61. The thread may be carried into the slot 59 by inserting it through the obliquely ar- 80 ranged slit 69 which extends from the end of the shell to the said slot. Likewise the thread may be carried to the aperture 61 by inserting the same through the slit 70 which connects the said aperture 61 with the rear edge of the shell. Because the front limb of 85 the thread loop is cast across the front of the bobbin casing, this front must be constructed so that no projections or rough surfaces are presented to hinder the passage of the thread thereacross. As previously stated, 90 the shell is formed at the top of the front portion thereof with an upstanding finger 64 which, as viewed in Fig. 12, is inclined slightly to the right of the vertical so that the left hand edge thereof may engage with 95 the shoulder 44 to thereby prevent movement in one direction of the bobbin casing with respect to the carrier. As clearly shown in several of the figures, it will be observed that this finger not only extends upward but is 100 arranged so that it projects toward the bearing rim of the carrier whereby the end thereof is located to the right hand side of the needle when the device is viewed from the front or operator's side thereof. Thus, as 105 the thread is delivered from the end of this finger, it will be guided to the right hand side of the needle, as viewed from the front of the machine. In machines having the hook rotating toward the operator if the 110 beak of the hook rotates in a plane to the right of the needle and the bobbin thread is delivered on the opposite side of the needle a stitch having a knot instead of a twist will 115 be produced. However, if the bobbin thread is delivered at the right hand side of the needle, a proper stitch will be formed. Con- 120sequently the means for delivering the thread in this manner is a very important feature of this invention. As far as I am aware, I 125 am the first to provide means for delivering the bobbin thread in this manner in a rotary hook sewing mechanism rotating in the di- 130rection described. It will be further ob- 135 served that because of this relation, the needle may be threaded from left to right, as viewed from the front or the operator's side of the machine. Hence, by providing means for delivering the bobbin thread at the right hand side of the needle, it is pos- 140

sible to form a proper stitch with a needle threaded from left to right. The advantages of having a needle threaded from left to right are well known in the art and the 5 utility of this provision for delivering the bobbin thread at the right of the needle will therefore be apparent. The side of the shell adjacent the shoulder 55 on the race is formed with a projection or shoulder 71, 10 which is adapted to coöperate with the shoulder 55 to prevent movement of the casing relative to the race. It will thus be apparent that the shoulders 55 and 71 prevent movement of said casing in one direction 15 and that the finger 64, abutting against the shoulder 44, prevents movement in the other direction, and hence the bobbin casing is securely held against rotation in the race. Adjacent the shoulders 71 the shell is formed 20 with another projection or shoulder 72. In inserting the bobbin casing in the race, it is necessary to place it therein with the finger 64 substantially horizontal, then the casing is rotated to bring the finger in contact with 25 the shoulder 44, whereby the bobbin casing is pushed farther inward to bring the shoulders 55 and 71 into engagement. The shoulder 72 is provided for the purpose of preventing the bobbin casing from moving 30 axially inward too far when it is first placed in the casing with the finger 64 horizontal. It will be apparent that as the opening in the race for the bobbin casing is eccentric, at 35 the top of the race and immediately below the shoulders 43 and 44, there is a slight space between the casing and the web 45. Consequently if the shoulder 72 were not provided the bobbin casing could move inward to its full extent and, upon rotation of 40 the same to bring the finger 64 in contact with the shoulder 44, the casing would bind in the race. Consequently the function of the shoulder 72 is to act as a stop or safety device to prevent the casing from being incorrectly inserted in the race. 45

It will be observed that the inclined front wall 34 of the hook ring has particular utility in combination with the inclined front wall 42 of the race, inasmuch as the wall 34 50 delivers or guides the upper thread onto the front wall of the race. If the inclined front wall 34 were made cylindrical instead of conical, it is apparent that the finger 64 would be much longer and of different shape 55 and project laterally in a different manner. However, because of this conical wall 34, the diameter of the hook ring is maintained at a minimum and the finger 64 may be shaped so that the whole device may be located very close to the needle plate 167. Hence there is more or less of an intimate 60 relation between all these parts of the device. Furthermore, it will be observed from Figs. 4 and 5, especially, that the finger 64 acts as a 65 very efficient guide for the upper thread

loop when it is being drawn upward by the take-up, thus preventing twists and snarls in the same.

Referring to Figs. 3 to 5, inclusive, it will be observed that the bobbin thread passes 70 from the end of the finger 64 upwardly and in an inclined direction through the needle aperture 66. In previous constructions of rotary hook mechanisms the bobbin thread has been delivered from the bobbin at the left of 75 the vertical and guided to the needle aperture so that it is bent around the left hand edge of the aperture, as viewed in these figures. It will be observed in this mechanism, however, that the said bobbin thread passes 80 in almost a straight line from the end of the finger 64 through the needle aperture to the cloth, the right hand lower edge of the needle aperture being slightly beveled as at 73 for this purpose. Referring to Fig. 5, it is 85 apparent that as the thread loop is drawn up from the position there shown into the cloth to form the stitch, the bobbin thread between the end of the finger 64 and the cloth forms substantially a straight guide for the loop 90 and offers practically no resistance to its passage therealong. In the other types of mechanisms in which the bobbin thread is delivered from the bobbin at the left of the vertical and drawn around the left hand edge of 95 the needle aperture, it is obvious that the thread loop must be drawn along the curved path of said bobbin thread and that there is more or less binding when the said loop passes between the edge of the needle aperture and the bobbin thread. Considerable 100 tension in the machine is required in order to pull the loop along at this portion of its movement. Furthermore, because of the 105 bend in the bobbin thread and pull of the loop at an angle to the said thread, it is obvious that there is considerable liability of breaking the bobbin thread. With the device herein disclosed, however, as the loop is guided along the substantially straight bobbin thread, there is practically no resistance to its passage therealong and a much weaker 110 tension on the thread may be used. Consequently as there is less stress on the thread there is less liability for breakage and the 115 speed of the machine may be increased over that heretofore used.

The different positions of the rotary hook in the operation of the device are illustrated in Figs. 1 to 5 inclusive. Fig. 1 illustrates 120 the positions of the parts when the beak is beginning to seize the loop from the needle. Fig. 3 shows the positions of the parts after the loop taker has rotated through a little more than 90°. It will be observed that the inclined front wall 34 has guided the front limb of the loop onto the inclined front wall 42 of the race. Of course, this inclined wall 34 could be omitted from the rotary hook 125 and the front wall 42 of the race further in- 13

clined so as to perform the function of guiding the front limb of the loop onto the front surface of the bobbin casing. However, if this wall 42 alone were depended upon, it 5 would be necessary to incline it a little more than shown in the drawings, thus requiring a somewhat larger diameter for the rotary hook. As the increased diameter of the rotary hook would increase the peripheral 10 speed thereof and the violence with which the beak would seize the loop from the needle, the advantages of keeping down the said diameter even by a very small amount are obvious. The rotary hook continues to rotate in a clockwise direction from the position shown in Fig. 3 until the front limb of the thread loop has been guided onto the front of the bobbin casing. Then the take-up begins to operate and pull up on the 15 thread loop. If this loop is pulled up too rapidly it will catch on the nose 26 of the loop taker, this nose thus performing the function of preventing snarls or unnecessary twists in the loop. When this nose 26 passes by the hook or nose 37 on the race, the loop will be released from the notch formed between the hooks 36 and 37 and will be drawn into the position illustrated in Fig. 20 4, where it extends around the shoulders 43, 44 and the finger 64. The continued movement of the take-up will pull the loop from the shoulders 43, 44, along the curved finger 64 to the position illustrated in Fig. 5. Thus, it will be apparent that this curved 25 finger guides and keeps distended the loop, thereby preventing twists or tangles. Furthermore, as explained previously, the loop is guided onto the bobbin thread so that it may be pulled therealong with the minimum 30 of friction and in a substantially straight path. When the loop is drawn from the shoulders 43, 44, that is, from the position of Fig. 4 into the position of Fig. 5, it will be observed that the depressions 48 in the 35 shoulders act to guide the thread loop under the projection 46 on the stationary member 47.

Although the inclined front wall on the 40 rotary hook is shown and described in connection with a hook mechanism rotating toward the operator, it is obvious that it is equally well adapted for use in hook mechanisms revolving away from the operator; also that the feature of the invention which 45 consists in delivering the bobbin thread through the needle aperture without making a sharp bend around the edge of the aperture is independent of the direction of rotation of the hook mechanism.

60 Having thus described the invention, what is claimed and desired to be secured by Letters Patent is:

1. In combination with a reciprocating needle adapted to be threaded from the operator's left to right, a rotary hook revolv-

ing toward the operator, a bobbin and means for delivering the bobbin thread at the right of the needle.

2. In a stitching mechanism, a rotary hook, a carrier mounted therein, a bobbin casing in the carrier, said carrier having an inclined front wall to guide the front limb of the thread loop upon the front surface of the bobbin casing and said rotary hook having a beak and an inclined front 75 wall arranged circumferentially in rear of the beak and projecting axially to cooperate with the first mentioned wall in guiding the thread.

3. A rotary hook for stitch forming mechanism comprising a ring having a beak and an axially projecting wall inclined toward the axis arranged circumferentially in rear of the beak and extending around a portion 80 only of the ring.

4. A rotary hook for stitch forming mechanism comprising a ring having a notch formed therein with a beak at one edge thereof, a member extending over the notch and circumferentially in rear of the beak for a portion of its circumference, one edge of the member in front of the beak constructed to constitute a thread deflector and in rear of the beak said member having an axially projecting wall inclined toward the axis. 90

5. A rotary hook for stitch forming mechanism comprising a ring having a notch formed therein with a beak at one edge thereof, a member extending over the notch and circumferentially in rear of the beak for a portion of its circumference, one edge of the member in front of the beak constructed to constitute a thread deflector and in rear of the beak said member having an axially projecting wall inclined toward the axis and 100 at the base of the beak said member and ring having a lug on one part fitting in a recess in the other to constitute a throat between the parts.

6. In a rotary hook sewing mechanism, a 110 bobbin casing having a projecting finger arranged to deliver the bobbin thread at the operator's right of the needle.

7. In a rotary hook sewing mechanism rotatable about a horizontal axis, a bobbin 115 casing, means for holding said bobbin casing against rotation, and means for delivering the bobbin thread at the operator's right of the needle.

8. In a rotary hook sewing mechanism 120 rotatable about a horizontal axis, a bobbin casing having means for delivering the bobbin thread in front, and at the operator's right, of the needle.

9. In a rotary hook sewing mechanism, a 125 bobbin casing having a projecting finger arranged to deliver the bobbin thread in front, and at the operator's right, of the needle.

10. In a sewing mechanism, the combina- 130

- tion of a reciprocating needle, a needle plate having an aperture for the needle and threads, a rotary hook device having a bobbin casing therein, and means for delivering the bobbin thread through the aperture to the material being sewed without bending the same around the edges of the aperture, said means including a finger carried by a stationary part of said device and extending to a point radially outside of the path of the hook, said point being on a substantially straight line passing through said aperture. 10
11. In a sewing mechanism, a rotary hook, a carrier therein having a projection at the top thereof, means coöperating with said projection to hold the carrier stationary, a bobbin casing in said carrier, and means for holding the casing against rotation, said means including a finger projecting radially outside of said carrier and engaging the side of said projection on the carrier. 15
12. In a sewing mechanism, a rotary hook, a carrier therein having a projection at the top thereof, means coöperating with said projection to hold the carrier stationary, a bobbin casing in said carrier, means for holding the casing against rotation, said means comprising a finger on the casing engaging the side of said projection to prevent rotation in one direction, and coöperating shoulders on the carrier and casing to prevent rotation in the other direction. 20
13. A rotary hook for stitch forming mechanism comprising a ring having a notch formed therein with a beak at one edge thereof, a member extending over the notch and circumferentially in rear of the beak for a portion of its circumference, one edge of the member in front of the beak constructed to constitute a thread deflector and in rear of the beak said member having an axially projecting wall. 25
14. In a sewing mechanism, the combination of a reciprocating needle, a needle plate having an aperture for the needle and threads, a rotary hook device having a bobbin therein, and means for delivering the bobbin thread above the device and in front of the needle whereby the said thread passes through the aperture in substantially a straight line. 30
15. A rotary hook sewing mechanism, including a non-rotative part, and a finger carried by said part and formed to deliver the bobbin thread at the operator's right of the needle. 35
16. A rotary hook sewing mechanism including a non-rotative part, and a curved finger carried by said part and projecting to a point radially outside of the rotary hook and at the operator's right of the needle and formed to deliver the bobbin thread at this point and to guide the upper thread loop onto the bobbin thread as it is drawn up to the fabric. 40
17. A rotary hook sewing mechanism including a bobbin casing and a stationary carrier, a finger projecting from the casing arranged to deliver the bobbin thread at the operator's right of the needle and coöperating with the carrier to prevent rotation of the casing in one direction relative to the carrier. 45
18. In a sewing mechanism, the combination of a reciprocating needle, a rotary hook rotatable in a plane parallel to and at one side of the needle, a stationary carrier, a bobbin casing, and means for delivering the bobbin thread at the same side of the needle as the hook. 50
19. In a sewing mechanism, in combination, a needle plate having an aperture for the needle, a rotary hook, a bobbin, and means for delivering the bobbin thread at a point radially outside the path of the hook, said point being on a substantially straight line passing through the said aperture. 55
20. A rotary hook sewing mechanism including a rotary hook, a stationary carrier, a bobbin casing, and a finger carried by the casing for delivering the bobbin thread at a point radially outside of the path of the said hook, and arranged to coöperate with the stationary carrier to hold the casing against rotation in one direction. 60
- In testimony whereof I affix my signature. 65

RICHARD K. HOHMANN.
